UNITED STATES PATENT OFFICE.

JESSE O. WILLIAMSON, OF LEWISTOWN, ILLINOIS.

SHADE-ROLLER BRACKET.

1,332,013.

Specification of Letters Patent. Patented Feb. 24, 1920.

Application filed July 30, 1918. Serial No. 247,444.

To all whom it may concern:

Be it known that I, JESSE O. WILLIAMSON, a citizen of the United States of America, residing at Lewistown, in the county of Fulton and State of Illinois, have invented new and useful Improvements in Shade-Roller Brackets, of which the following is a specification.

The invention seeks to provide, as its principal object, a shade roller bracket particularly adapted for attachment to a window frame without marring the latter, the device effecting a clamping grip on the upper transverse portion of the inside architrave of the frame.

A further object of the invention is to provide adjusting means contained in the device whereby the latter may be adjusted to suit various widths of such inside architrave as before mentioned, the adjustment being of a character to make any adjustment obtained positive.

A still further object of the invention is the provision of a device of this character which is simple in construction, durable and effective in operation and inexpensive to manufacture.

Other and further objects will appear in the following detailed description.

To the exact construction in which it is shown and described, the invention is not to be restricted. The right is reserved to make such changes or alterations as the actual reduction to practice may demand, in so far as such changes or alterations are comprehended in spirit by the annexed claims.

In the accompanying drawings:

Figure 1 is a front elevational view of the top inside architrave of a window frame, a pair of the improved brackets being shown attached thereto.

Fig. 2 is a perspective view of one of the improved brackets.

Fig. 3 is a section on the line 3—3 of Fig. 2.

Fig. 4 is a section on the line 4—4 of Fig. 2.

Fig. 5 is a perspective view of a modification of one of the clamping members comprising the bracket.

Fig. 6 is a top plan view of the structure shown in Fig. 5.

Referring to the drawings, there is shown the upper architrave 1 of a window frame to which are attached the two improved brackets, the two being identical with the

exception of the one being the reverse of the other because of mounting on opposite sides of the window frame. Since the two brackets are alike a description of the one will suffice for both. The bracket comprising the clamping member 2 is formed substantially in the shape of an L, thus providing the leg 3 and the leg 4. This clamping member 2 is made preferably of sheet metal of sufficient thickness to permit its retaining its shape after having been once formed. At a selected point in the leg 3 of the clamping member, the stock of which the clamping member is made is bent at right angles to itself, then again bent into a plane parallel with the plane of the leg, then bent back again toward the leg, thus providing an inset portion 5 in which there is carried the arm 7, the main or body portion of which is provided with the slot 6. This inset portion 5 is so formed as to provide a transversely disposed rib 7^a on its outer face which rib may engage in the slot 6. The arm 7 is secured to the clamping member 2 by the bolt 7^b, as shown.

The arm 7 is formed with a right angularly disposed portion 8 at the terminal of which there is an upstanding stud 9, the latter being designed to receive one end of a curtain pole which, prior to attachment to the stud, has formed in it a transversely disposed hole into which the stud enters. Between the stud and its point of connection with the body portion of the arm 7, the right angularly disposed portion 8 is provided with the shade roller stud receiving recess 10. This recess 10 is made either rectangular or round in shape, depending on whether it receives the round or flattened stud of the shade roller, there being of course two of the brackets now being described, one of which has the round recess and the other the rectangular.

Cooperating with the clamping member 2 there is a second clamping member 11. This latter is also L-shaped, being formed with the legs 12 and 13. The leg 12 on its inner face has secured to it a felt or rubber mat 14 to prevent its scarring the window frame, since it is designed to engage on the under face of the top inside architrave, which under face is of course a finished surface. The clamping members 2 and 11 are operatively connected together by means of a screw 15, which if to be tool-operated is provided with the usual kerf for a screw

driver, or if to be hand-operated, is provided with the usual wings.

The clamping member 2 has formed in its leg 3 between the inset portion 5 and the lower extremity the longitudinal slot 16 and on that face which faces the leg 12 of the clamping member 11 is provided with the teeth or corrugations 17, the adjoining face of the leg 12 of the said clamping member 11 being provided with teeth 18, designed to interlock with the teeth 17 when the screw 15 is tightened, inasmuch as the screw 15 passes loosely through the slot 16 and threadingly engages the clamping member 11 in the leg 12 near the upper or free end of the latter.

A screw 19 passes transversely through the leg 4 of the clamping member 2 with which leg it threadingly engages and this screw is designed for setting against the upper edge of the architrave 1.

In the attaching of the invention to a window frame, the clamping members 2 and 11 are adjusted so that the legs 4 and 13 are a distance apart slightly greater than the width of the architrave 1, the screw 15 being loosened to effect this adjustment. On the retightening of the screw after the adjustment has been obtained, the engaging of the teeth 17 and 18 serves to positively maintain the adjustment. The bracket is then in condition for attachment to the architrave, the legs 4 and 13 being made to straddle the latter so that the mat 14 lies against the other under edge and screw 19 brought above the upper edge of the architrave. The tightening or screwing down of the screw 19 then brings the lower or free end into engagement with the upper edge of the architrave, thus securely attaching the device in place. When the two brackets comprising a pair have been thus attached on opposite sides of a window frame having been given the proper positions apart, they are in condition to receive in the recesses 10 a shade roller and on the studs 9 a curtain pole which has previously been provided with holes in which the studs may engage.

In Figs. 5 and 6 there is shown a modified form of clamping member to be used in place of the clamping member 11. This clamping member is provided with a leg 30 identical with the leg 12 of the clamping member 11, so that it may be attached to the clamping member 2 in the same way as is the clamping member 11. This leg 30 is formed at its lower end with a right angularly disposed portion 31 constituting a clamping jaw designed to engage the under edge of the architrave. This portion 31 is covered on its upper face by a rubber or felt mat 32 to prevent its marring the architrave

when the device is attached. This modified form of clamping member is made preferably from one piece of metal which, after being formed to provide the legs 30 and 31 is twisted through an angle of 90° at the end of the portion 31 to provide the extension 33, the face of which is intended to lie in a plane parallel with the plane of the window frame, between the sash and the architrave. This extension 33 is formed so that its offset forms the edges of the legs 31 and 30 next to the window frame, so that the extension 33 will be spaced from the window frame where it faces the latter. The extension is then inturned at the end providing a foot 34 which rests against the side of the frame adjacent to the sash. At a point between the foot 34 and where it connects with the portion 31, the extension is provided with a transverse hole 35 in which the round stud of a shade roller may be supported. Of course the bracket used on the opposite side of the window will be provided with a recess formed on the upper edge of the extension 33, the recess being of the usual shape to receive the flattened stud of the shade roller.

This modified form of clamping member is designed to support shade rollers where they are held in between the side of the window frame, such as is customary in case of very thick house walls with the resultant increased thickness of window framing.

In the event that the improved bracket is used on a window frame of which corner blocks form a part of the architrave, the arm 7 may be attached to the clamping member 2 by having the rib 7a engage the slot 6. This construction provides for setting the arm 7 out from the frame a sufficient distance to prevent interference by the block, the usual block projecting out beyond the face of the architrave.

The invention having been described what is claimed as new and useful is:

A device of the kind described comprising a duality of L-shaped clamping members, means adjustably connecting the clamping members together, the one of said members having an intermediate portion of its longer leg offset to provide an inset on the rear face thereof, the said offset portion on the outer face having a transversely disposed rib, an arm provided with means for supporting a shade roller and being formed with a longitudinal slot through which said rib passes, a screw whose shank passes through the offset portion and the rib and whose head rests in the inset, and a nut threadingly engaged with the shank of the screw and bearing upon the arm.

In testimony whereof I affix my signature.
JESSE O. WILLIAMSON.
